UNITED STATES PATENT OFFICE.

PHILIPP WAGNER, OF NEW YORK, N. Y.

IMPROVEMENT IN BRUSH-SOCKETS.

Specification forming part of Letters Patent No. 137,515, dated April 1, 1873; application filed
March 13, 1873.

To all whom it may concern:

Be it known that I, PHILIPP WAGNER, of New York, in the county and State of New York, have invented a new and useful Improvement in Brush-Sockets; and I do hereby declare the following to be a full, clear, and exact description of the same, reference being had to the accompanying drawing forming part of this specification, in which—

Figure 1 represents a side elevation of a brush made according to my invention. Fig. 2 is a transverse section; and Figs. 3, 4, and 5 are detail views of the same.

The invention relates to the construction of a bridge for sheet-metal sockets of brushes, (mainly paint-brushes,) so as to secure strength and cheapness in the manufacture. The invention consists in the employment of ribs or corrugations on the side edges, whose subjacent concavities receive the side edges of the socket.

In the drawing, A represents the bristles of a paint-brush, fastened by rivets *a* into a socket, B, which is made of sheet metal. Over the middle of upper edges pass the handle-socket

bifurcations *c c*, which are soldered thereto. D is the bridge, whose edges are corrugated or channeled on the under side so as to form the strong grooved ribs *d d*, into whose subjacent cavities the upper edges of the socket B are sprung, and there held and soldered. This bridge-piece, as well as the other pieces, is first cut out, as shown in Fig. 3, and then provided with corrugations *d d*, as shown in Figs. 4 and 5, by rolling or stamping dies of corresponding construction.

By this construction the brush is made much stronger, more durable, and cheaper than those now manufactured.

Having thus described my invention, what I claim as new, and desire to secure by Letters Patent, is—

The bridge D, having strong subjacent-grooved ribs *d d* applied to the upper edges of socket A, as and for the purpose described.

PHILIPP WAGNER.
